UNITED STATES PATENT OFFICE.

GUSTAVE E. HOGLUND, OF CHICAGO, ILLINOIS, ASSIGNOR TO SELIG POLYSCOPE CO., OF CHICAGO, ILLINOIS, A CORPORATION OF ILLINOIS.

MOVING-PICTURE MACHINE.

971,891.

Specification of Letters Patent.

Patented Oct. 4, 1910.

Application filed November 4, 1909. Serial No. 526,318.

To all whom it may concern:

Be it known that I, GUSTAVE E. HOGLUND, a citizen of the United States, residing at Chicago, in the county of Cook and State of Illinois, have invented certain new and useful Improvements in Moving-Picture Machines, of which the following is a specification.

The present invention relates to means for passing the film in front of a light aperture with an intermittent movement; and has for its object to construct mechanism which will make such movement positive and in a manner to give the best results, to a construction which will be operated from the main driving shaft of the machine, to a construction which is simple of formation and operation, and to a construction in which a slight displacement of the parts by usage will not render the operation of the chain of mechanism imperfect. And the invention further consists in the features of construction and combination of parts hereinafter described and claimed.

In moving-picture machines it is essential that the film be passed in front of the light aperture with an intermittent movement, such movement consisting of a relatively long period of rest in front of the light aperture and an instantaneous movement away from the aperture. If the movement away from the aperture is not instantaneous, it will result in a flickering of the picture when projected upon the screen, a condition which is highly undesirable for a great variety of reasons. The quicker the picture is moved away from the light aperture, the more the flickering will be reduced, so that when a very rapid movement is effected, the flickering will be dispensed with sufficiently to answer all practical purposes.

In the drawings, Figure 1 is a side view of the mechanism of the present invention located in operative position within a frame work of a moving-picture machine; Fig. 2 a section on line 2—2 of Fig. 1; Fig. 3 a section on line 3—3 of Fig. 2; Fig. 4 a section on an enlarged scale on line 4—4 of Fig. 2; Fig. 5 a section through the gear wheel operating the feed rolls and the spring for actuating said feed rolls; and Fig. 6 a section on line 6—6 of Fig. 2.

The device is positioned within a casing 7 employed in moving-picture machines of any well-known and ordinary type of construc-

tion, in the side walls of which casing is journaled a main driving shaft 8, to which is attached a handle 9, or other well-known means for imparting rotation thereto. Fixedly attached to said shaft is a member 10, consisting of a hub 11 and a projecting finger 12. Located adjacent to the member 10 is a gear wheel 13 loosely mounted upon the shaft 8 and provided with a pin 14 adapted to be contacted by the finger 12. Mounted loosely upon the shaft 8 is a gear wheel 15 formed with a housing 16, in which is positioned a coil spring 17, one end of which is attached to the shaft 8 and the other end of which is attached to the gear wheel 15.

Journaled in the side walls of the frame work 7 is a shaft 18, upon which is fixedly attached a pinion 19 meshing with the gear wheel 13, and on which shaft is loosely mounted a gear wheel 20 meshing with the gear wheel 15. The shaft also has fixedly secured thereto a miter gear 21 meshing with a miter gear 22 carried by a shaft 23 mounted within a sleeve 24, and upon the upper end of the shaft 23 is a miter gear 25 meshing with a miter gear 26 mounted upon a shaft 27 mounted in a sleeve 28, which shaft carries a shutter 29, formed in the usual manner, to cut off and admit light through the light aperture during the passage of the film past the aperture.

Located upon the shaft 18, and preferably lying adjacent to the side wall of the casing, is a cam 30 located within an opening 31 formed in a slidable plate 32. The plate is composed of a downwardly extending portion 33, in which the opening 31 is located and a laterally extending portion 34, which has a portion cut away to provide an opening 35, into which project fingers 36 and 37 formed on the plate 32. The plate is provided along its upper edge with slots 38, into which project pins 39 affixed in the side walls of the casing.

Journaled in the side walls of the frame work 7 is a shaft 40, to which is fixedly attached a ratchet wheel 41 located in the opening 35 in the plate 32, and having its teeth 42 so formed that one of them will be in contact with either the finger 36 or 37 when the plate is in the extreme position of movement in either direction. Fixedly attached to the shaft 40 are companion feed rolls 43 of the type ordinarily employed in moving-picture machines, and also fixedly attached

to the shaft 40 is a gear wheel 44 meshing with the gear wheel 20. The operation is as follows:

When power is applied to rotate the shaft 8, the member 10 will be revolved, and when the finger 12 is brought into contact with the pin 14, the gear wheel 13 will be revolved in unison with the member 10. The rotation of the gear wheel 13 will revolve the gear wheel 19, imparting movement to the shaft 18, which will actuate the gearing to rotate the shutter 29, and, at the same time, actuate the cam 30 to move the plate 32 back and forth. With the parts shown as in Fig. 6, a movement of the cam will throw the sliding plate 32 forward, bringing the finger 37 out of engagement with the tooth 42 of the ratchet 41, and leaving the shaft 40 free to be revolved.

The gear wheels 15, 20 and 44 serve as a means for producing a spring tension upon the shaft 40 in the following manner: As the shaft 8 is rotated, the coil spring 17 will be wound up and a spring tension placed on the gear wheel 15, which is held against rotation while the spring is being wound up by the gears 20 and 44, which provide locking means for preventing such rotation. The shaft 40, being under spring tension, when the finger 37 is withdrawn from engagement with the teeth 42, will be revolved with great rapidity, actuating the feed rolls 43 rapidly, and moving the picture away from the light aperture with great rapidity. As the finger 37 is withdrawn from contact with one of the teeth 42, the finger 36 will be brought into position to contact one of the teeth 42, and such contact will result in the stopping of the revolution of the shaft 40 and of the feed rolls 43. But the finger will not be in position to engage the tooth until the finger already in engagement with the tooth has been withdrawn therefrom, so that the ratchet will be fully released at such time and free to rotate a distance equal to the distance between the teeth. The shaft 8, being a continuously revolving shaft, the spring 17 will be wound up during the periods of rest of the shaft 40, so that the same degree of spring tension is always present upon the shaft when the finger 36 or 37 is withdrawn from engagement with one of the teeth 42.

While I have shown and described my device as working in conjunction with a shutter, it may be found in practice that the movement of the film away from the light aperture will be fast enough so that a shutter need not be used. I, therefore, do not desire to limit myself to a shutter working in combination with my film feed.

I claim:

1. In a device of the class described, the combination of a shaft carrying a set of feed rolls, a main driving shaft, a shaft intermediate the two first named shafts, means con-

nected to the main driving shaft for rotating the intermediate shaft, means on the intermediate shaft for permitting and arresting the rotation of the shaft carrying the feed rolls, means operating independently of the above mechanism, for initially placing a spring tension upon the shaft carrying the feed rolls, and means for regenerating said spring tension during the periods of rest of the shaft carrying the feed rolls, substantially as described.

2. In a device of the class described, the combination of a shaft carrying a set of feed rolls, a main driving shaft, a shaft intermediate the two first named shafts, means connected to the main driving shaft for rotating the intermediate shaft, means for permitting the main driving shaft to rotate independently of the intermediate shaft for a predetermined length of time, to place an initial spring tension on the shaft carrying the feed rolls, means on the intermediate shaft for automatically permitting and arresting the rotation of the shaft carrying the feed rolls, and means for automatically regenerating the above mentioned spring tension during the periods of rest of the feed rolls, substantially as described.

3. In a device of the class described, the combination of a shaft carrying a set of feed rolls, a main driving shaft, a shaft intermediate the two first named shafts, a gear wheel loosely mounted on the main driving shaft, means attached to the main driving shaft for rotating said gear wheel, means for permitting the rotation of said shaft independently of said gear wheel, to place an initial spring tension upon said shaft carrying the feed rolls, a gear wheel fixedly secured upon the intermediate shaft and meshing with the gear wheel on the main driving shaft, means actuated by the intermediate shaft for permitting and arresting the rotation of the shaft carrying the feed rolls, and means for regenerating the above mentioned spring tension during the periods of rest of the feed rolls, substantially as described.

4. In a device of the class described, the combination of a shaft carrying a set of feed rolls, a main driving shaft, a shaft intermediate the two first named shafts, a gear wheel loosely mounted on the main driving shaft, a member fixed on the main driving shaft, consisting of a hub and a finger extending out from said hub, a pin on the gear wheel adapted to be contacted by the finger, the main driving shaft rotating independently of the gear wheel until the pin and finger contact, such rotation serving to place an initial spring tension on the shaft carrying the feed rolls, a gear wheel fixedly attached to the intermediate shaft, means actuated by the intermediate shaft for permitting and arresting the rotation of the

shaft carrying the feed rolls, and means for regenerating the above mentioned spring tension during the periods of rest of the feed rolls, substantially as described.

- 5 5. In a device of the class described, the combination of a shaft carrying a set of feed rolls, a main driving shaft, a shaft intermediate the two first named shafts, a gear wheel loosely mounted on the main driving 55
10 shaft, means attached to the main driving shaft for rotating said gear wheel, a gear on the intermediate shaft meshing with the gear wheel on the main driving shaft, a cam carried by the intermediate shaft, a 60
15 slideable plate actuated by the cam, a ratchet wheel on the shaft carrying the feed rolls and coöperating with the sliding plate to permit and arrest the rotation of said shaft, and means for applying a spring tension 65
20 to said shaft, substantially as described.

6. In a device of the class described, the combination of a shaft carrying a set of feed rolls, a main driving shaft, a shaft intermediate the two first named shafts, a gear 75
25 wheel loosely mounted on the main driving shaft, means attached to the main driving shaft for rotating said gear wheel, a gear wheel on the intermediate shaft meshing with the gear wheel on the main driving
30 shaft, a cam carried by the intermediate shaft, a slideable plate actuated by the cam, said plate consisting of a downwardly extending portion having an aperture formed therein, against the walls of which the protruding portion of said cam contacts, and a laterally extending portion having an aperture formed therein, into which projects oppositely extending fingers, a ratchet wheel on the shaft carrying the feed rolls, one of 80
35 the extending fingers being in contact with a tooth on the ratchet wheel when the plate is at either extremity of its movement, and the teeth being so positioned that during a period in the movement of the plate, neither
40 45 finger will be in engagement with a tooth, leaving the ratchet free to rotate a distance equal to the length of the tooth, and means for applying a spring tension to the shaft carrying the feed rolls, substantially as de- 90
50 scribed.

7. In a device of the class described, the combination of a shaft carrying a set of feed rolls, a main driving shaft, a shaft intermediate the first two named shafts, means connected to the main driving shaft for 55
55 rotating the intermediate shaft, means on the intermediate shaft for permitting and arresting the rotation of the shaft carrying the feed rolls, a gear loosely mounted on the main driving shaft, a coil spring attached at one end to said shaft and at the other end to said gear wheel, means for rotating the main driving shaft independently of the intermediate shaft to wind up 60
60 said spring, an idler gear wheel loosely mounted on the intermediate shaft and meshing with the gear wheel on the main driving shaft, and a gear wheel fixed to the shaft carrying the feed rolls and meshing with the idler gear wheel on the intermediate 65
70 shaft, substantially as described.

8. In a device of the class described, the combination of a shaft carrying a set of feed rolls, mechanism for automatically permitting and arresting the rotation of said 75
75 shaft, means operating independently of the last named mechanism for initially placing a spring tension upon the shaft carrying the feed rolls, and means for automatically placing such spring tension upon the shaft carrying the feed rolls during the periods when said shaft is at rest, substantially as described.

9. In a device of the class described, the combination of a shaft carrying a set of feed rolls, mechanism actuated from a main driving shaft for automatically permitting and arresting the rotation of said shaft, means operating independently of the last named shaft for initially placing a spring 85
85 tension upon the shaft carrying the feed rolls, means actuated from the main driving shaft for automatically placing such spring tension upon the shaft carrying the feed rolls during the periods when the last named 90
95 shaft is at rest, substantially as described.
